Letters Patent No: 822, Dated Aug 5th 1856.

The schedule referred to in these Letters Patent and making part of the
same.

To all whom it may concern: .

Be it known that we, Samuel Pierce and J. J. Dudley
of Troy in the County of Rensselaer and State of New York, have invented
or produced, a new and original design for parlor stoves, And we do
hereby declare that the following is a full, clear and exact description
of the same, reference being had to the annexed perspective drawing

and the letters of reference marked thereon, making part of this specification.

The description of our design for parlor stoves is as follows, viz; A, is the bottom plate with moulding (a a) B is the base front plate, decorated upon its surface with ornaments (b b) B', is the end base plate with ornaments (b' b'). C is the middle front plate, having the ornaments (c, d, e, f,) disposed upon its surface, C', is the middle end plate with ornament (g). D, is the centre plate with mouldings (h) E, is the upper front plate having the ornamental openwork door (i) and side ornaments (j, k, l, m,) E', is the upper end plate, with the panel ornament (n). G, is the top plate with the ornamental urns (o, p, q) arranged upon its surface, H, is the leg having scroll edges (r) and ornament (s) upon its face.

Having fully described our design for parlor stove, that we, claim as new and desire to secure by letters patent, is;

The ornamental design and configuration of parlor stove, the same as herein described and shown in the annexed perspective drawing
